UNITED STATES PATENT OFFICE

GEORGE A. WILLIAMS, OF DECATUR, ILLINOIS, ASSIGNOR TO WILLIAMS SEALING CORPORATION, OF DECATUR, ILLINOIS, A CORPORATION OF ILLINOIS

TAMPER-PROOF SEAL FOR CONTAINERS

Application filed October 6, 1926. Serial No. 139,824.

This invention relates to a novel construction of tamper proof seal for the nozzle or spout of a sheet metal container, the object being to provide a seal which must be removed before the contents can be poured out, but which will not interfere with the application of the cap to the sealed nozzle or spout; and another object is to provide a seal of this character which can be removed 10 without injury to the nozzle or spout, thus permitting the cap to be replaced in case it is so desired, the seal being intended to show to the purchaser that the original contents of the package are intact at the time of purchase.

The invention, therefore, consists in the details of construction hereinafter fully described and set forth in the appended claim.

In the drawings forming a part of this 20 specification, Fig. 1 is a perspective view of a sheet metal container having its nozzle closed by a cap; Fig. 2 is a top plan view of a nozzle with tamper proof seal therein and cap removed; and Fig. 3 is a sectional view of 25 nozzle seal and cap.

The cap and nozzle are now standard articles of manufacture and are both disclosed in my Patent No. 1,339,245.

Referring to the drawings, 10 indicates the 20 container, 11 the nozzle or spout and 12 the cap with fastening lever 13.

The upper edge of the nozzle or spout is rolled inwardly as shown at 14 and fitting 25 into the mouth of the nozzle is a concavo-convex sheet metal tamper proof seal 15 having an outwardly projecting flange 16, which is pressed firmly into wedging action with the inwardly rolled edge 14 of the nozzle or spout, the diameter of the seal itself being 40 such that it will just pass into the mouth of the nozzle and the outward curve of the seal make a tight fit upon the inwardly rolled edge of the nozzle.

This seal being of thin sheet metal can 45 be easily removed when desired and after the seal is removed the contents can be wholly or partially poured out. In case only a part of the contents is removed the cap 12 can be replaced and securely seal the nozzle.

50 When the seal has been fastened in the

nozzle mouth, the cap is fastened upon the end of the nozzle and effectively seals the same, and constitutes the main seal for the container.

The construction of the seal is such, and 55 its position in the nozzle is such that it does not interfere with the application of the cap.

The sheet metal seal can have any legend or notice stamped thereon to indicate to the purchaser that the contents of the container 60 have not been tampered with.

Having thus described my invention, what I claim is:

The combination with a nozzle having an inwardly rolled upper edge, of a cup-like 65 sheet metal seal adapted to fit into the mouth of said nozzle, the upper edge of said seal flaring outwardly and contacting with the inner convex edge of said inrolled portion, and a cap having a lining contacting with 70 said inrolled edge portion of the nozzle and outwardly flaring edge of the seal.

In testimony whereof, I hereunto affix my signature.
